UNITED STATES PATENT OFFICE.

JOHN E. RILEY, OF NEW YORK, N. Y.

ELEVATOR-SIGNAL.

SPECIFICATION forming part of Letters Patent No. 388,918, dated September 4, 1888.

Application filed March 5, 1888. Serial No. 266,267. (No model.)

To all whom it may concern:

Be it known that I, JOHN E. RILEY, a citizen of the United States, residing at New York city, in the county of New York and State of New York, have invented certain new and useful Improvements in Signal Attachments for Elevators; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention consists of an improved contrivance for an automatic alarm-signal attachment to passenger and other elevators, for giving notice in advance of its approach to landings and other places, and particularly to the basement, for warning persons who may happen to be present in such positions as might expose them to injury, for escape in time for avoidance, as hereinafter fully described, referring to the drawings, in which—

Figure 1 is a front elevation of an elevator having my improved attachment and showing the action of the signal when the elevator descends; and Fig. 2 is a detail of the apparatus, showing a contrivance to allow the elevator to ascend without sounding the alarm, which is part of my contrivance for such cases as do not require the signal on the up run.

On the top of the elevator-carriage *a*, I arrange a gong, *b*, or other approved sounder on any approved stand, *c*, with a striking hammer, *d*, having an actuating-spring, *e*, which strikes the gong when the hammer is lifted or withdrawn therefrom; and for withdrawing the hammer preparatory to striking I have arranged the hammer-staff with an extension, *f*, projecting into the notches of the safety-rack, so that the points of the rack lift or withdraw the hammer from the bell when the carriage descends, and thus cause the sounding of the alarm on the downward run. I may of course contrive for the sounding of the hammer on the upward course also; but as that is

not generally required I have connected the extension part *f* of the hammer-staff to the other part, *d*, by the joint *h*, allowing it to yield for passing the points of the teeth on the up run, and have suspended said extension by a spring, *i*, to return it to the normal position after passing the teeth, and have provided the lap-extension *j* from the pivot *h* along part *d*, for making the staff rigid as against the teeth on the down run for working the bell.

This attachment is more important in factories and other places where the elevators run infrequently and are not well guarded or protected in the basement to prevent persons getting under them, and where doors are not always closed along the way on the floors above.

I am aware that an alarm-signal has been arranged on the car in connection with studs specially provided along the elevator-way for operating the hammer; but my improvement is such as is operative by the safety-rack, so as to avoid the expense of specially providing the studs therefor.

What I claim, and desire to secure by Letters Patent, is—

1. The combination of the bell located on an elevator car, the safety-rack, the bell-hammer having the jointed and overlapped extension-staff, and the bell-hammer-retracting spring, said staff being adapted to engage the teeth of the rack and vibrate the hammer when the car moves downwardly and to swing free without affecting the hammer when the car moves upwardly, all substantially as set forth.

2. The combination, with the elevator car or carriage and the safety-rack, of the bell attached to the car, the jointed and overlapped hammer-staff, hammer-working spring, and the hammer-staff-extension-controlling spring, substantially as described.

In testimony whereof I affix my signature in presence of two witnesses.

JOHN E. RILEY.
